UNITED STATES PATENT OFFICE.

WILLIAM JOHN HENLEY AND SPENCER TIMOTHEY AXTELL, OF OSWEGO,
NEW YORK.

OAR FOR ICE-BOATS.

SPECIFICATION forming part of Letters Patent No. 288,801, dated November 20, 1883.

Application filed October 9, 1883. (No model.)

To all whom it may concern:

Be it known that we, WILLIAM J. HENLEY and SPENCER T. AXTELL, of Oswego, in the county of Oswego, in the State of New York, have invented new and useful Improvements 5 in Ice-Boats, of which the following, taken in connection with the accompanying drawings, is a full, clear, and exact description.

This invention consists in a novel construction of an oar designed for propelling an ice-boat.

The invention is fully illustrated in the annexed drawings, wherein Figure 1 is a plan view of an ice-boat provided with our improved oar. Fig. 2 is a side view of said boat. Fig. 3 is an enlarged detail view of the oar, and Fig. 4 is a transverse section on line x x in Fig. 3.

Similar letters of reference indicate corresponding parts.

A represents an ice-boat of any suitable style and construction, mounted on runners R R, and provided with suitable oar-locks, B B.

C denotes the oar, which we form of sections 25 a a , connected end to end by a longitudinally-yielding splice or joint consisting of a sleeve, b , which is at one end rigidly secured to the end of one of the oar-sections, and is provided at the opposite end with longitudinal slots c c , 30 in which slide the ends of the bolts d d , which pass through the other oar-section fitted movably in said end of the sleeve b , said slots being of sufficient length to allow the outer end of the oar to retract a distance equal to the versed 35 sine e of the segment, which is usually described by the oar when operated in water, as illustrated by dotted lines in Fig. 1 of the drawings.

In order to normally hold the oar in its distended position, we place in the sleeve b an 40 expansive spring, f , which forces the outer oar-section outward and yields to the inward

pressure exerted by the confinement of the point of engagement of the extremity of the oar on the ice, as demonstrated by dotted lines 45 in Fig. 1 of the drawings.

The extremity of the oar is provided with a socket, g , which we prefer to connect to the oar detachably, so as to admit of applying to the oar interchangeably different devices for 50 engaging the ice or paddles for operating in water, as may be desired. In the socket g is inserted at right angles to the oar a spur or spike, t , secured in position by a set-screw, u , said spike serving to obtain the requisite hold 55 on the ice for propelling the boat.

Having described our invention, what we claim is—

1. An ice-boat propelling-oar, provided at its outer end with a spur or spike for engaging 60 with the ice, substantially as set forth.

2. An ice-boat propelling-oar, consisting of longitudinally-extensible sections and means for engaging with the ice on the end of the oar, as set forth.

3. An ice-boat propelling-oar, composed of sections joined end to end by a longitudinally-yielding splice and a spring for normally holding 65 said sections in a distended condition, substantially as and for the purpose set forth.

4. The combination, with an oar, of the socket g , spur t , and set-screw u , substantially as and for the purpose shown and set forth.

In testimony whereof we have hereunto signed our names and affixed our seals, in the 75 presence of two attesting witnesses, at Oswego, in the county of Oswego, in the State of New York, this 1st day of October, 1883.

WILLIAM JOHN HENLEY. [L. S.]
SPENCER TIMOTHEY AXTELL. [L. S.]

Witnesses:

W. J. STARK,
ALLEN POUCHER.
